CLAIM

The ornamental design for a pedestal table, as shown and described.

DESCRIPTION

FIG. 1 is a perspective view of the pedestal table of the present invention;

FIG. 2 is a top view of the pedestal table of FIG. 1; and, FIG. 3 is a front view of the pedestal table of FIG. 1.

The pedestal table is symmetrical and the side views are identical as are the front and back views. The bottom is flat and devoid of surface ornamentation.
